US00D370728S

United States Patent [19]**Edgar et al.**[11] **Patent Number:** **Des. 370,728**[45] **Date of Patent:** ****Jun. 11, 1996**[54] **CONTAINER FOR ORTHOPEDIC CASTING MATERIAL**[75] Inventors: **Jason L. Edgar**, Bloomington; **Michael J. Jarzynski**, Roseville; **James E. Nash**, St. Paul, all of Minn.[73] Assignee: **Minnesota Mining and Manufacturing Company**, St. Paul, Minn.[**] Term: **14 Years**[21] Appl. No.: **17,854**[22] Filed: **Jan. 24, 1994****Related U.S. Application Data**

[63] Continuation-in-part of Ser. No. 98,617, Jul. 28, 1992, abandoned, which is a continuation-in-part of Ser. No. 964,511, Oct. 21, 1992, abandoned, and a continuation-in-part of Ser. No. 40,624, Mar. 31, 1993, abandoned, which is a continuation-in-part of Ser. No. 964,511, Oct. 21, 1992, abandoned.

Primary Examiner—Louis S. Zarfas*Assistant Examiner*—I. Simmons*Attorney, Agent, or Firm*—Gary L. Griswold; Walter N. Kirn; Stephen W. Bauer[57] **CLAIM**

The ornamental design for a container for orthopedic casting material, as shown and described.

DESCRIPTION

FIG. 1 is a perspective view of a container for orthopedic casting material showing our new design;

FIG. 2 is a top view thereof;

FIG. 3 is a front view thereof;

FIG. 4 is a left side view thereof;

FIG. 5 is a bottom view thereof;

FIG. 6 is a back view thereof; and,

FIG. 7 is a right side view thereof.
